UNITED STATES PATENT OFFICE

SAMUEL W. HYATT, OF CONNERSVILLE, INDIANA, ASSIGNOR TO INDIANA LAMP CORPORATION, OF CONNERSVILLE, INDIANA, A CORPORATION

AIRPLANE LANDING LIGHT

Application filed March 21, 1931. Serial No. 524,330.

This invention relates to a landing light for airplanes, and more particularly a stationary light adapted to be mounted on the under surface of the wings, or fuselage.

5 The principal object of the invention is to provide a fixed lamp of this character adapted to be partially housed within the wing and partially projecting therefrom at an angle for deflecting the air current. The projecting portion is associated with a streamline housing for minimizing the wind resistance.

10 One feature of the invention resides in the arrangement of the lens with respect to the reflector and source of light, wherein a forward beam is obtained through the medium of suitable prisms formed through the lens, which beam is adapted to illuminate the ground ahead of the airplane. Another portion of the lens is free from prisms for permitting a direct beam to be projected downwardly and only slightly forwardly for illuminating the ground in front of the plane in the more immediate vicinity.

15 Other features of the invention reside in the construction and mounting of the reflector and support therefor within the wing and the mounting of the lens thereon.

20 The full nature of the invention will be understood from the accompanying drawings and the following description and claims:

In the drawings, Figure 1 is a diagrammatical illustration of an airplane with the lamps mounted therein indicating the direction of the respective beams of the lamps. 25 Fig. 2 is a central vertical section through a portion of the airplane wing and the lamp mounted therein. Fig. 3 is a front elevation of the lamp when mounted in position.

30 In the drawings, there is illustrated an airplane 10 having a pair of wings 11 in which a dome housing 12 is mounted. Said housing is formed of sheet metal and is provided with the flanges 13 which are rigidly secured to the under surface of the wing by the bolts 14.

35 Secured to the dome housing on the rear side thereof there is a socket support 15 secured in position by the bolts 16 and insulating washers 17. Supported by the support 40 there is a socket 18 having a battery con-

nection 19 and ground connection 20. Said socket mounts an incandescent lamp bulb 21 within the dome in the usual manner. Surrounding the bulb and secured by the bolts 16 to the dome there is a parabolic reflector 55 22, the upper portion of which extends upwardly within the dome and the lower portion extends downwardly therefrom.

45 Secured about the exposed lower periphery of the reflector 22 and to the underside of the wing there is a streamline housing 23 for minimizing the air resistance resulting from the exposed portion of the lamp.

50 Mounted over the front of the reflector there is a lens 24 having a metal rim 25 located about the peripheral edge and provided with an ear 26. The peripheral edge of the reflector is provided with a grooved flange 27 in which an annular gasket 28 is mounted against which the metal rim of the lens is 65 adapted to bear. The lens is secured over the open face of the reflector and against the gasket 28 by a screw 29 extending through the ear 26 and projection 30 secured to the streamline housing. By this means the lower portion of the lens is clamped tightly in 70 position against the gasket 28 and thereby secured to the reflector. At the upper end of the lens a bronze spring 31 is riveted to the dome housing in position to engage and yieldingly press against the lens for holding it in 75 position. Thus the lens is yieldingly secured over the front face of the reflector at the upper end thereof by the spring 31 and removably locked at the lower end thereof by the 80 screw 29.

85 The lens is provided with a plurality of light deflecting prisms 32 extending laterally across the inner surface thereof. Said prisms are so formed as to bend the rays of 90 light reflected by the parabolic reflector from the source upwardly with respect to the axis of the reflector, whereby this group of rays in the operative position of the lamp will be projected substantially forward for illuminating the ground ahead of the airplane.

95 The upper portion of the lens is free from said prisms so that the light rays will project therethrough without refraction to be directed parallel with the axis of the lamp to 100

illuminate the more immediate portion of the ground in front of the plane. The outer surface of the lens is provided with the usual vertical flutes or prisms for spreading the rays laterally so that the beams of light will cover a substantial area.

By reason of the above described construction, a stationary airplane lamp is provided having a minimum of wind resistance and which will permit of ready removal of the lens for giving access to the bulbs, the lens serving to not only spread the light laterally, but provide two distinct beams, one for forward illumination and the other for more immediate illumination.

The invention claimed is:

1. The combination with a wing of an airplane, of an airplane landing light including a dome-shaped housing mounted therein above the under surface thereof, a parabolic reflector fixedly mounted so that its axis extends forwardly and downwardly of the airplane, a portion of said reflector extending upwardly into said dome and a portion thereof of extending downwardly therefrom, a source of light mounted within said reflector, a streamline housing secured to the rear of the exposed portion of said reflector and to the underside of the wing for minimizing wind resistance, and a lens removably secured over the face of said reflector for receiving the parallel rays projected therefrom, a portion of said lens being provided with prisms for deflecting the rays and directing them more forwardly than downwardly to illuminate the remote forward area while the remainder of said lens is free from said deflecting prisms for permitting the rays to pass therethrough parallel with the axis of the reflector to illuminate the more immediate forward area.

2. The combination with a wing of an airplane, of an airplane landing light including a recess formed in the under surface of the wing, a metal dome secured to said wing and extending upwardly into said recess, a lamp socket mounted on the exterior of said dome, a parabolic reflector mounted on the interior of said dome to one side thereof, means for securing said socket and reflector thereto, a lamp bulb carried by said socket and having a source of light substantially at the focal point of said reflector, the upper portion of said reflector extending within said housing and the lower portion thereof without said housing and inclined so that the axis thereof is directed forwardly and downwardly from the airplane, a streamline housing secured to the rear of the reflector and the under surface of said wing for minimizing wind resistance, a flange formed about the periphery of said reflector for receiving a gasket therein, a lens having a rim mounted about the periphery thereof, a spring member secured to the under side of said dome housing adapted to bear against the upper edge of the lens

for holding it under spring tension against said gasket, and an ear protruding from the rim of the lens on the lower side thereof adapted to removably secure said reflector to the streamline housing.

3. The combination with a wing of an airplane, of an airplane landing light including a recess formed in the under surface of the wing, a metal dome secured to said wing and extending upwardly into said recess, a lamp socket mounted on the exterior of said dome, a parabolic reflector mounted on the interior of said dome to one side thereof, means for securing said socket and reflector thereto, a lamp bulb carried by said socket and having a source of light substantially at the focal point of said reflector, the upper portion of said reflector extending within said housing and the lower portion thereof without said housing and inclined so that the axis thereof is directed forwardly and downwardly from the airplane, a streamline housing secured to the rear of the reflector and the under surface of said wing for minimizing wind resistance, a flange formed about the periphery of said reflector for receiving a gasket therein, a lens having a rim mounted about the periphery thereof, a spring member secured to the under side of said dome housing adapted to bear against the upper edge of the lens for holding it under spring tension against said gasket, an ear protruding from the rim of the lens on the lower side thereof adapted to be removably secured to said reflector and streamline housing, and means formed on said lens for deflecting the light rays passing therethrough at an angle to the axis of the reflector for illuminating the more remote forward area, a portion of the lens being free thereof for permitting rays to be directed parallel with the axis of the reflector to illuminate the more immediate area.

In witness whereof, I have hereunto affixed my signature.
